UNITED STATES PATENT OFFICE.

EMIL NEUDÖRFFER, OF STUTTGART, GERMANY.

ELECTRIC POCKET-LAMP.

1,074,377.

Specification of Letters Patent. Patented Sept. 30, 1913.

Application filed October 9, 1911. Serial No. 653,699.

To all whom it may concern:

Be it known that I, EMIL NEUDÖRFFER, a citizen of the German Empire, residing at Stuttgart, in the Kingdom of Wurttemberg, 5 Germany, have invented certain new and useful Improvements in Electric Pocket-Lamps; and I do hereby declare the following to be a full, clear, and exact description of the invention, such as will enable others 10 skilled in the art to which it appertains to make and use the same.

This invention relates to an improved electric pocket lamp and the improvement consists substantially in an intermediate part 15 which receives the lamp and which is fixed in the battery casing being provided for separating the necessary cells. By inserting the lamp together with its stem and reflector in the intermediate piece between the cells, 20 that is to say, by the use of an intermediate piece which also serves for receiving the incandescent lamp, the pocket lamp is made extremely small, light and handy. The intermediate piece is formed as a frame, so 25 that the frame for the cells is utilized for receiving the incandescent lamp. The cells may be of any suitable shape and any suitable number, preferably the ordinary circular cells are employed. The frame-like 30 intermediate piece may equally well be made of an insulating material or of metal, but then with the latter suitable insulations must be provided. Now it is not absolutely necessary to employ an intermediate piece 35 as above described as a yoke formed of a suitable metal strip for instance of U-shape, may also be employed, in which case again a suitable insulation must be provided, as in the previously mentioned intermediate 40 piece.

The invention will now be more particularly described with reference to the accompanying drawings, in which some forms of construction are shown.

45 Figure 1 is a front view showing the improvement; while Fig. 2 is a sectional plan view; Fig. 3 shows the frame-like intermediate piece in perspective; while Figs. 4 and 5 are views of different forms of pocket 50 lamps fitted with the improvement.

For keeping apart, that is to say, separating the two cells *a* necessary in the ordinary pocket lamp, a frame-like intermediate piece *b* which serves as support for the cells *a* is by this invention provided, which intermediate piece may be made of insulating material or even of metal if insulation be employed. The battery, that is to say, the cells *a* and intermediate piece *b*, is preferably held together by a case *c*, band or the like (Figs. 1 and 2). In accordance with this invention the intermediate piece *b* may also serve for receiving the incandescent lamp *d* for which object the intermediate piece *b* is provided with a suitable recess 65 or socket *e* (Fig. 3). The incandescent lamp *d* is then inserted between the two cells *a*.

The invention is adapted both for the ordinary form of electric pocket lamps and 70 also for those having the form of a watch or money box (Figs. 4 and 5), but of course the form of the pocket lamp is immaterial.

I declare that what I claim is:—

1. A portable pocket lamp, comprising two 75 spaced cells, a band embracing said cells, an intermediate piece separate from the cells and band interposed between the cells for holding the same in spaced relation against the band, and a lamp seat formed in said 80 intermediate piece.

2. A portable pocket lamp comprising two spaced cells, a band embracing the same, an intermediate block between the cells for holding the same in spaced relation, and a 85 lamp seat located in said block.

3. A portable pocket lamp comprising two spaced cells, an intermediate piece located between the cells and having recesses corresponding to the shape of the cells for receiving the same, a case surrounding said cells, and the intermediate piece, and a lamp seat formed in said intermediate piece. 90

In testimony whereof I affix my signature, in presence of two witnesses.

EMIL NEUDÖRFFER.
